STEAM-TRAP.

1,072,405.

Specification of Letters Patent.

Patented Sept. 2, 1913.

Application filed October 6, 1914. Serial No. 585,564.

To all whom it may concern:

Be it known that I, JOHN A. BUTCHER, a citizen of the United States, and a resident of York, York county, Pennsylvania, have invented certain new and useful Improvements in Steam-Traps, of which the following is a specification.

My invention is an improvement in steam traps, and consists in certain novel constructions, and combinations of parts, hereinafter described and claimed.

The object of the invention is to provide a simple, efficient and easily operating device of the character specified, wherein a special chamber or passage is provided for separating the steam and water prior to their admission to the trap proper, and wherein the water of condensation will be automatically retained at a depth sufficient to prevent the escape of steam, but not high enough to block the inlet.

In the drawings forming a part hereof, is shown a vertical section of the improvement.

25 The embodiment of the invention shown comprises a casing consisting of a base plate 10, approximately circular and slightly cupped as shown, and the said base plate is provided with a marginal lateral flange 11, having in the upper face thereof an annular groove 12, approximately semi-circular in cross section. The base plate is provided with a central threaded opening 13 for engagement by a hollow standard 14, which is threaded at its lower end into a cup 15 on a base 16. The cup 15 is provided with a lateral internally threaded nipple 17 and a blow-off pipe 18 is threaded into the nipple. A dome shaped cover or casing 19 is provided at its lower edge with a marginal lateral flange 20, which seats upon the flange 11 of the base plate, and is secured thereto by cap screws 21. The said screws are journaled in plain openings 22 in the flange of the base plate, and engage threaded openings 23 in the flange of the cover. The lower face of the flange 20 is provided with an annular approximately semi-circular groove 24 registering with the groove 12 of the flange 11, and a packing strip or gasket 25 is seated in the registering grooves, to make a fluid tight joint between the cover and the base plate. The cover is provided in its side wall with a substantially vertical

55 passage 26, extending from a point adjacent

to the flange 20 on one side of the said cover to the top thereof. The passage communicates with the interior of the casing near the base plate, by means of a port 27, and at the upper end of the passage a valve casing 28 is threaded into an opening in the cover and communicates with the passage, the connection being controlled by a valve 29. At approximately the vertical center of the passage a nipple 30 is arranged in the side wall of the cover, communicating with the passage, and an inlet pipe 31 is threaded into the nipple. At the opposite side of the casing from the inlet, a reducing union 32 is threaded into a nipple 33 in the casing wall, and an outlet pipe 34 is threaded into the union. The passage 35 through the union is conical as shown, gradually increasing in cross section from within outward, and the outlet pipe 34 is provided with a diaphragm 36, having a central opening whose inner end forms a valve seat for the valve, to be described. The pipe is internally threaded at 37, outside of the diaphragm to permit the connection of other pipes, if desired. A valve 39 cooperates with the seat, and the said valve has one end conical for engaging the seat, while one end of a stem 40 is threaded into an opening in the other end, and is engaged by a set screw 41 threaded through the valve, to hold the said valve on the stem. The opposite end of the stem 40 is provided with spaced ears 42, between which is secured one arm 43 of an elbow lever, pivoted at 44, to a bracket 45, on the inner face of the reducing unit 32. The other arm 46 is the long arm of the elbow lever, and extends radially to the approximate vertical center of the casing.

A bearing 47 is provided in a bracket 48, and is supported in alignment with the hollow standard 14, and above the inner end thereof. A similar bracket 49 is arranged at the top of the casing, and supports a bearing 49 in vertical alignment with the bearing 47. A float 50 in the form of a hollow sphere is provided at each end with an internally threaded nipple 51, one of which is engaged by the end of a rod 52, and the other by the end of a similar rod 53. Each of the rods passes through the bearing of the adjacent bracket 47 or 48, as the case may be. The float may rise and fall in the casing, and is guided in its movement by the rods and the bearings. The rod 52 is pro-

vided near its upper end with a transverse opening 54, through which extends the long arm 46 of the elbow lever above mentioned. It will be evident that the rising and falling movement of the float will open and close the outlet valve 39. When the float is lifted, the valve is opened, and when the float descends the valve is closed. The upper end of the rod 53 extends through an opening 55 in the top of the casing, and the said opening communicates with the passage 26. The lower end of the rod 52 extends into the hollow standard 14. The valve casing 38 is directly opposite the opening 54, and the opening 54 for the arm 46 of the elbow lever increases in length from the center toward each end.

The operation of the improvement is as follows: The steam enters through the inlet pipe 31, and through the passage 26 passes into the casing, the interior thereof is the condensing chamber, where the said steam is condensed. The water in the chamber prevents the escape of the steam, and as the amount of water increases, the float is lifted, and the outlet valve 39 is opened, permitting the excess to escape. The depth of the water in the chamber is dependent upon the position of the float. As soon as enough water escapes to permit the valve 39 to seat, the float cannot descend farther, since the engagement of the valve with its seat prevents further downward movement of the arm 46 of the elbow lever. The arrangement of the passage 26, which communicates with the chamber above and below the normal water level, equalizes the pressure and gives a continuous discharge of water. Any scale or sediment that may enter with the steam will, on account of the shape of the base plate, settle in the hollow standard or in the cup, and may be blown off whenever desired. It will be understood that the pipe 18 is controlled by a suitable valve to prevent the escape of water from the casing.

The float and all the internal parts of the casing are preferably of copper, brass, or other non-corrodible material, to insure long life, and to prevent jamming or clogging due to rust. The passage 26 is cast with and in the cover, and the packing ring or gasket 25 is preferably of copper. The valve 28 is a vent for permitting the escape of undesirable gases from the chamber and preventing its getting air bound.

It will be evident that the inlet port is at approximately the center of the float, and that the outlet port is at a lower level than the float, so that the water in the chamber can never rise sufficiently high to enter the inlet.

The passage 26, as before stated, forms a separating chamber, wherein the steam and water are separated. With this construc-

tion, there can be no possible blocking of the inlet, even when the water is moving at a greatly increased speed, since the steam can pass immediately upward, as soon as it issues from the inlet pipe.

I claim:

1. A steam trap comprising a casing consisting of a shallow cup shaped base plate having a marginal lateral flange, provided on its upper face with an annular groove, said plate having a central opening, a base provided with an internally threaded cup having a lateral opening, a hollow standard threaded at one end into the cup and at the other into the central opening of the base plate, a cover having a marginal lateral flange seated on the flange of the base plate and provided with an annular groove registering with the groove of the base plate flange, a packing ring seated in the grooves, cap screws connecting the flanges, said cover having a vertical passage in its wall extending from near the flange to the top of the cover and communicating with the interior of the casing at each end, an inlet pipe communicating with the passage at approximately its center, an outlet port at the opposite side of the casing and near the base plate, a valve controlling the said port, an elbow lever pivoted to the interior of the casing, and having one arm connected with the valve, a float in the casing, rods extending vertically from the float in opposite directions, and a guide connected with the casing for each rod, one of said rods having a transverse opening through which extends the other arm of the elbow lever, the float being at a higher level than the outlet.

2. A steam trap comprising a casing consisting of a base plate provided with a central opening, a base having a hollow cup with a lateral opening, a hollow standard seated at one end in the cup and engaging at the other the central opening of the base plate, a cover seated on the base plate and secured thereto, said cover having a vertical passage in its wall extending from near the bottom to the top of the cover and communicating with the interior of the casing at each end, said passage having an inlet near its center, the cover having an outlet port at the opposite side from the passage, a valve controlling the said port, a float in the casing, rods extending vertically from the float in opposite directions, a guide in the casing for each rod, one of the rods having a transverse opening and an elbow lever pivoted to the casing and having one end engaging the opening and the other the valve.
